Patented July 13, 1976

240,567

DOLL CARRIER

Susan Tatum, 34 E. 3rd St., New York, N.Y. 10003

Filed Nov. 6, 1974, Ser. No. 521,257

Term of patent 14 years

Int. Cl. D3—02

U.S. Cl. D87—1 A

FIG. 1

FIG. 2

FIG. 3

FIG. 4

FIG. 5

FIG. 1 is a rear elevational view of a doll carrier showing my new design;

FIG. 2 is a front elevational view;

FIG. 3 is a bottom plan view;

FIG. 4 is an unfolded front elevational view with the straps shown as broken away for convenience of illustration; and

FIG. 5 is an unfolded rear elevational view with the straps shown as broken away for convenience of illustration.

I claim:

The ornamental design for a doll carrier, as shown and described.
